(57) **CLAIM**

The ornamental design for a handle for a medical instrument, as shown and described.

DESCRIPTION

FIG. 1 is a top, front, right perspective view of a handle for a medical instrument;

FIG. 2 is a bottom, rear, left perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom thereof.

The broken lines illustrate portions of the handle for a medical instrument and form no part of the claimed subject matter. In certain applications, the illustrated embodiment of a handle for a medical instrument can be a handle for a medical scope such as an endoscope or a ureteroscope.
